C. W. FERGUSON.
CONDUCTOR WIRE REELING MECHANISM FOR TELEPHONES.
APPLICATION FILED FEB. 18, 1913.

1,116,402.

Patented Nov. 10, 1914.

UNITED STATES PATENT OFFICE.

CHARLES W. FERGUSON, OF BOWER, WEST VIRGINIA.

CONDUCTOR-WIRE-REELING MECHANISM FOR TELEPHONES.

1,116,402.

Specification of Letters Patent. Patented Nov. 10, 1914.

Application filed February 18, 1913. Serial No. 749,230.

To all whom it may concern:

Be it known that I, CHARLES W. FERGUSON, a citizen of the United States, residing at Bower, in the county of Braxton and State of West Virginia, have invented certain new and useful Improvements in Conductor - Wire - Reeling Mechanism for Telephones; and I do hereby declare the following to be a full, clear, and exact description 10 of the invention, such as will enable others skilled in the art to which it appertains to make and use the same.

This invention relates to telephones, and it more particularly relates to conductor 15 wire reeling mechanism for telephones.

The primary object of the invention is to provide convenient and thoroughly practical means for storing the terminal sections of a telephone conductor within the base of 20 a desk-telephone-stand.

Another object of the invention is to provide for properly connecting the terminal sections within the base of the telephone in such manner that the electrical circuit is 25 uninterrupted, regardless of the position of the reel on which the terminal sections are wound.

Another object of the invention is to embed the terminal sections within a flat tape 30 so that they may be conveniently and smoothly wound upon the reel.

Another object of the invention is to provide a device of this character which operates automatically for winding and 35 unwinding the tape.

Another object of the invention is to provide for holding the reel at any desired position.

Another object is to provide for automatically releasing the reel when the receiver is 40 replaced on its support.

Another object is to provide a mechanism of this character which is simple of construction and operation; compact, durable, 45 economical of manufacture and maintenance, and thoroughly efficient.

Other objects and advantages may be recited hereinafter and in the claims.

In the accompanying drawings, which 50 supplement this specification, Figure 1 is a vertical sectional view through the base and standard of a desk-telephone, the transmitter and receiver being shown in elevation, and the electric circuits and connections being diagrammatical. Fig. 2 is a

reduced horizontal sectional view through the base on the line 2—2 of Fig. 1.

Referring to these drawings, in which similar reference characters correspond with similar parts throughout the several views, 60 the telephone stand consists of the usual form of shaft or standard 5 and the base 6, the latter being apertured and screw-threaded at 7, and thereby adapted to be fitted to any ordinary shaft 5. The base 65 comprises a casing having a bottom 8, said bottom being formed with a central cylindrical boss 9 which is centrally apertured and screw-threaded for receiving an axle 10. A reel or drum 11 is mounted for rotation 70 on the axle 10, and a spring 12 has one end secured to the boss 9 and its other end secured to the reel 11, by means of a pin 13. The reel is formed with a drum section 14 to which the tape 15 is connected at 16. This 75 tape may be of any suitable fabric or other flexible material, and has the conductor wires *a*, *b*, *c*, *e* and *g* embedded therein, these wires being insulated from each other and held in fixed relation to each other 80 throughout the length of the tape. The drum section is perforated at 17 for allowing the conductor wires to pass from the tape into the chamber 18 of the reel. The disk, which comprises the upper section of 85 the reel, is apertured at 19 for allowing the conductor wires to pass upward therethrough and connect respectively with rings 20, 21, 22, 23 and 24, of conducting material; these rings being separated from the 90 reel by means of a disk 25 of insulating material.

An apertured brush holder 26 is secured to the casing 6, and carries brushes 27, 28, 29, 30 and 31, which are held in contact with 95 the respective rings 20 to 24 inclusive by means of springs 32. It will be seen, therefore, that when the reel is rotated the brushes are in sliding contact with the respective rings. The conductor wires *g*, *e*, *c* 100 and *b* are connected to the brushes 27, 28, 29 and 30 respectively, while the wires *c* and *b* are also connected with each other. The brush 31 is normally in contact with an element 34 of a circuit-closer which is securely 105 seated upon the axle 10. The elements 34, 35, 36 and 37 constitute bars or strips of springy conducting material which are firmly seated in a base 38 of non-conducting material, said base being fixed on the 110

axle 10 by means of an upwardly extending screw-threaded stud 39, or by other suitable means.

The conductor rings 20 to 24 inclusive are insulated from each other, as indicated at 40, while the brushes and circuit-closer elements are insulated from each other; and from the casing and reel, in an obvious manner, except that the brush 31 and element 34 are normally in contact, so that the bell circuit is normally closed.

The receiver 41 is supported by the usual lever-arm 42 which is pivoted to the shaft 5 at 43. A plunger rod 44 is pivoted to the lever-arm at 45 and carries an inverted cone or wedge 46 of insulating material.

The plunger 44 is provided with a pivot 47 which extends through a slot in one end of a lever 48 which is pivoted at 49 to an arm 50 extending from the wall of the casting 6. Upon the peripheral portion of the reel is mounted a tooth-ring or ratchet member 51, and the free end of the lever 48 is normally disposed over one side of the ring 51, and is adapted to be swung downward into engagement with the teeth of the ring. A pin or stud 52 extends into proximity or contact with said free end and coacts therewith for positively stopping and holding the ratchet member; so as to hold the reel in any desired position.

In operation, assuming that a person has just completed a phone message and hung up the receiver, the elements of the phone are substantially in the position shown in Fig. 1, the ratchet being released. As soon as the phone is returned to the desk, the spring 12 causes the reel to rotate to wind the tape 15 thereon, so that the tape will then be effectually stored within the base of the phone, out of the way of all persons. Now, assuming that the central operator calls in the usual manner, the current passes through the bell 53, conductor *a*, ring 20, brush 31, conductor element 34, connecting wire *b'*, brush 30, ring 21, and conductor wire *b*; so that the bell rings and calls the user. The user now picks up the phone-stand, and in drawing it toward him pulls the tape 15, which (as usual) has its outer end secured to the desk or wall, and in thus pulling the tape, he causes the reel to rotate, so as to wind up the spring 12. The user now lifts the receiver from the support 42, and the latter is raised by means of a spring 54, thereby raising the wedge 46; and actuating the lever 48, so that its free end engages with the ratchet 51 and holds the reel, so as to prevent it from turning and winding up the tape prematurely. The wedge 46 having been raised, the upper ends of the elements 34 and 37 spring into proximity, so as to contact with the elements 35 and 36 respectively, and close the respective circuits, at the same time opening the cir-

cuit between the arm of the brush 31 and the element 34, so that the bell circuit is broken and the receiver and transmitter circuits are closed. At this stage, the circuit passes from the positive line-wire *h* through the conductor wire *c*, ring 22, brush 29, and transmitter connection *c'*, to the transmitter 55, returning thence through the transmitter connection *d'*, circuit closer elements 35 and 34, connection *b'*, brush 30, ring 21, and conductor *b*; while the receiver circuit passes from the secondary coil of the transformer 56, through the conductor *e*, ring 23, brush 28, connecting wire *e'*, circuit closer elements 37 and 36 and conductor *f* to the receiver, returning through the conductor *g'*, brush 27, ring 24, and thence through the conductor *g*.

It will be noted that the conductor *b* constitutes the return conductor for the bell circuit and also for the transmitter circuit, so that only five conductors are required to complete the several circuits through the tape, while only two line wires are required, viz., *h* and *b*.

By means of the structural arrangement described in the foregoing, I effectually eliminate the annoyance of the terminal sections which usually become entangled and twisted upon the desk and which so often results in breakage of the phone, by these terminal sections becoming engaged with some article, and thereby being dragged from the desk onto the floor. Therefore, it will be seen that I have provided a device of this character which is fully capable of attaining the foregoing objects, in a thoroughly practical and efficient manner.

I do not limit my invention to the exact details of construction, combination and arrangement of parts, as herewith illustrated and described, but my invention may only be limited by a reasonable interpretation of the claims.

I claim:—

1. A desk telephone comprising a shank, a hollow base connected with the shank, a boss projecting upwardly from the center of the bottom of the casing, and within the same, a reel horizontally disposed within the casing and upon the top of said boss, a pin extending through the reel and threaded in said boss and providing a bearing for the reel, a concentric series of rings disposed upon the upper side of the reel and rotatable therewith, said rings being insulated from the reel and from each other, a tape having conducting wires embedded therein and having its free end secured to the reel, each of said wires being connected with one of said rings, a U-shaped brush-holder having its closed end secured to the casing and its free ends extending horizontally therein and in a vertical plane, brush members vertically slidible within said arms and each adapted

- to contact with one of said rings, springs disposed between said arms and surrounding said brushes and adapted to constantly hold the brushes in engagement with said rings, 5 means connecting the brush members for conducting currents to the transmitter and receiver, and a spring surrounding said boss and having one of its ends connected with said reel whereby the reel may be wound.
- 10 2. A desk telephone comprising a hollow shank and a hollow base, a winding reel disposed within the bottom of the base, a concentric series of rings disposed upon the upper side of the reel and being insulated 15 therefrom and from each other, a tape for conductor wires being secured to the reel and adapted to be wound thereupon, a plurality of brushes vertically and slidably supported within the base and adapted to contact with said rings, a pair of spaced and opposite spring fingers disposed within the base, a pair of spaced and oppositely disposed contacts positioned between said fingers and each adapted to be engaged by one 20 of said spring fingers, a receiver support pivoted to the shank, a rod connected with the receiver support, an inverted cone upon
- the free end of said rod and adapted to engage said spring fingers to hold the same out of engagement with said contacts, an arm 30 extending from one end of one brush, and contacting with one of said spring fingers when the spring fingers are engaged by said cone, a conductor connecting another of said brushes with said last mentioned spring finger whereby a circuit for ringing the telephone bell is made, conducting wires between one of said brushes and the contact of said last mentioned spring finger for closing the transmitter circuit when the cone 40 is raised from engagement with said spring fingers, conducting means connecting two other of said brushes with the other of said spring fingers and contacts whereby the receiver circuit is closed when the cone is 45 raised from engagement with said spring fingers.

In testimony whereof I have signed my name to this specification in the presence of two subscribing witnesses.

CHARLES W. FERGUSON.
